HAROLD W. MEYER, OF BROOKLYN, NEW YORK

APPARATUS FOR SNELL HOOK MANUFACTURE

Application filed August 14, 1931. Serial No. 557,077.

This invention relates to the manufacture of snelled hooks and the special objects of the invention are to supply the fish hooks to the trade with the snells straight and orderly and therefore easier to handle, neater and a more attractive article from the sales standpoint.

These and other desirable objects are attained in the present invention by setting up hooks in a stretching or snell straightening frame immediately following the snelling operation. The novel construction of this frame and other features of the invention will appear as the specification proceeds.

The drawing accompanying and forming part of the specification illustrates a simple commercial embodiment of the invention but it is to be understood that the structure may be modified and changed as regards this disclosure without departure from the true spirit and broad scope of the invention.

Fig. 1 is a front elevation of one of the frames or racks, illustrating a few of the hooks in place at one end of the frame; Fig. 2 is an enlarged cross-sectional view as taken on substantially the plane of line 2—2 of Fig. 1.

The form of the device herewith disclosed comprises a generally rectangular frame made up of side guides or rods 10 and 11 joined at top and bottom by the upper and lower tie rods 12, 13. For adjustment purposes the upper tie rod is shown as sleeved at 14, 15 over the ends of the side rods and as adjustably secured by set screws 16, 17. Similarly the lower tie rod is shown as sleeved over the side rods at 18, 19 and is adjustably held by set screws 20, 21.

For directly supporting the hooks and the frame, a rack bar 22 is illustrated carried by sleeves 23, 24 slidably engaged on the side rods and connected by a brace or cross head 25 which, in the example illustrated carries links 26 for supporting and reinforcing the intermediate portions of the rack bar 22. The notches 27 in the upper edge of the rack bar provide seats for the hooks, serving to hold the latter as designated at 28 in relatively close but properly spaced relation.

The shanks 29 of the hooks have the snells

30 attached thereto at 31 which latter are illustrated as having the usual loops 32 for attachment to the fishing tackle.

Mounted in the frame opposite the rack bar 22 is a bar 33 shown as adjustably supported by having end collars 34, 35 secured by set screws 36, 37 on the side rods 10, 11.

For engaging the loops of the snells, special spring holders 38 are provided, consisting in the illustration of hair pin wires which have the straight parallel legs 39, 40 sliding through guide openings 41, 42 in the cross bar and provided at the upper ends with the outturned hooks 43, 44 for engagement by the snell loops. These snell holders are independently tensioned in the disclosure by coiled springs 45 on the straight portions 39 of the retainers, said springs engaging the underside of the cross bar and acting against the looped lower ends 46 of the retainers.

For adjusting and for quick hook releasing purposes, the side bars of the frame are illustrated as toothed to form racks 47 engageable by the holding dogs 48 pivoted at 49 on the end sleeves of the upper, or hook holding bar 22. These latches are readily releasable through the medium of the handle levers 50 which latter are shown as acted on by springs 51 for holding the latches normally engaged with the respective racks.

The stroke or adjustment of the hook racking bar is shown as predetermined in the illustration by the stop collars 52 adjustably secured on the side rods of the frame by set screws 53.

In using the invention, the racking bars 22 and 23 are relatively adjusted, if need be, to properly hold the snelled hooks of the size or sizes which are to be racked, such adjustments being easily accomplished by loosening the set screws and sliding one or the other or both of the bars over the side posts or rods 10, 11. These adjustments are usually such that with the hooks caught in the notches in the upper bar and the loops of the snells caught to the spring holders of the lower bar, the snells will be drawn tight and straight in the manner indicated at the left in Figure 1. The usual method of placing the hooks in the frame is to first catch the loop of the snell

80

over a hook of one of the spring holders and to then snap the hook up over the complementary notch in the upper rack bar. The frame may be thus quickly filled with the 5 hooks, the hook terminals 43, 44 of the spring retainers enabling the hooks to be placed in either side of the frame, or if desired in both sides of the frame. Usually, however, only a 10 single hook will be held by a spring retainer so that individual spring tension will be applied to each snell.

With the hooks in place in the frame they may be all treated at once, for instance for removing any burrs or the like at the wrappings 15 31, which can be accomplished quickly by passing a blow-torch flame along these wrapped joints. The entire group of hooks may be simultaneously treated in other ways, for example by dipping the rack in a solution 20 which will temporarily soften the snells. When withdrawn from such solution the rack may be placed aside to permit the snells to dry after which the hooks can be quickly detached from the frame upon releasing the 25 latches 48, to permit the upper rack bar to slide down over the side posts sufficiently for the hooks to become disengaged from their seats in the rack bar. After a frame is thus cleared of hooks, the rack bar may be slid up 30 against its stops 52 in proper position to receive the next load of hooks, and to permit this quick return movement, the rack teeth 47 may be inclined as indicated at 54 to permit the latches to snap over the same in the 35 return stroke.

As the structure may be modified and changed in various respects, all within the true and intended scope of the invention, it should be understood that the terms employed herein have been used in a descriptive 40 rather than in a limiting sense, except possibly, for such limitations as may be imposed by the state of the prior art.

What is claimed is:

- 45 1. A device of the character described including a pair of side guides, tie rods connecting the ends of said side guides, a rack bar mounted for vertical sliding movement on the portions of said side guides between said tie rods, a cross-bar mounted on said portions of said side guides between said tie rods and beneath said rack bar, each of said side guides including a series of rack teeth and said rack bar having latching means to cooperate with said rack teeth for supporting said rack bar in a selected elevated position, means adjustable on the side guides to limit the upward travel of said rack bar, a plurality of devices extending upwardly through said cross-bar and tensioning springs on said devices, said rack bar being notched and thereby adapted to support the hook portions of a plurality of snelled fish hooks in spaced relation, and said devices being adapted to engage the free 55 ends of the snells of said fish hooks to indi-

vidually maintain said snells in tautened condition.

2. In a device of the character described, a frame including a pair of vertical side guides, upper and lower tie rods detachably secured to said side guides, a crosshead mounted for vertical sliding movement on said side guides, said crosshead including a rack bar and an overhead member having suspension devices to support said rack bar intermediate its ends, a cross-bar movably mounted on said side guides and including means for attachment to the latter in a selected height adjustment position, each of said side guides including a series of rack teeth, said crosshead including latch devices to cooperate with said rack teeth for supporting said crosshead in different elevated positions, adjustable stop devices on said side guides to limit the upward travel of said crosshead, a plurality of hook devices extending upwardly through said cross bar and tensioning springs on said hook devices, said rack bar being adapted to support the hook portions of a plurality of snelled fish hooks and said hook devices being arranged to engage the looped portions of the snells of said fish hooks to individually maintain said snells in tautened condition for straightening the same.

3. Apparatus for the manufacture of snell hooks comprising a frame consisting of side guides secured together in spaced parallel relation, cross bars engaged with said side guides and one adjustable on said side guides toward and away from the other cross bar, quick-releasable means for retaining said movable cross bar spaced from the other cross bar and readily releasable to permit bodily movement of said cross bar toward the other cross bar, one of said cross bars having spaced notches to receive and space the hook portions of a number of snelled fish hooks and spring tensioned holders on the other cross bar in line with the hook notches to receive the free ends of the snells of said fish hooks to thereby individually tension the snells and whereby upon actuation of said quick-releasable holding means, the one cross bar may be shifted toward the other to release the individually tautened fish hooks as a group.

4. Apparatus for the manufacture of snell hooks comprising a frame having side guides, cross bars connecting said side guides and one freely movable on the side guides toward and away from the other, individual snell tensioning devices in spaced relation on one of the cross bars and the other cross bar having correspondingly spaced holding means for the opposite ends of snelled fish hooks and quick-releasable means for holding the freely movable cross bar spaced from the other cross bar and whereby by release of such means, said freely movable cross bar may be quickly shifted in the frame to release all of the individually tensioned snelled hooks.

5. Apparatus for use in the manufacture of snelled hooks and comprising a frame having substantially parallel cross bars relatively movable toward and away from each other, 5 individual snell tensioning devices on one of the cross bars and each adapted for engagement by one end of a snelled hook and the other cross bar having holding means for the opposite ends of the snelled hooks and relatively spaced to thereby maintain the individually tensioned snelled hooks in definitely spaced orderly arrangement in the frame and quick-releasable means for retaining the cross bars in relatively separated relation and whereby by release of such means, the cross bars may be quickly approached to effect the release from the frame of the entire group of individually tensioned snelled hooks. 10
6. Apparatus for use in the manufacture 20 of snelled hooks and comprising a frame having substantially parallel cross bars relatively movable toward and away from each other, individual snell tensioning devices on one of the cross bars and each adapted for engagement by one end of a snelled hook and the other cross bar having holding means for the opposite ends of the snelled hooks and relatively spaced to thereby maintain the individually tensioned snelled hooks in definitely spaced orderly arrangement in the frame and quick-releasable means for retaining the cross bars in relatively separated relation, whereby by release of such means, the cross bars may be quickly approached to effect the release from the frame of the entire group of individually tensioned snelled hooks and regulatable stop means adjustable to fix the relative separating movement of the cross bars and whereby after discharge of the 30 snelled hooks from the frame the cross bars of the frame may be quickly reset to take a fresh group of the snelled hooks. 40
7. Apparatus for use in the manufacture 45 of snelled hooks, comprising a frame composed of side rods, a tie rod connecting said side rods in spaced relation at one end, a cross bar connecting opposite end portions of the side rods in spaced relation, a cross bar freely slidable on the side rods between the tie rod and the first mentioned cross bar, snell tensioning means carried by one of the cross bars and the other cross bar having means for engagement by opposite end portions of snelled hooks and whereby a number of hooks 50 may be engaged and held under tension between said cross bars and means for retaining the freely slidable cross bar in position separated a desired distance from the other cross bar, said retaining means being quickly-releasable to enable quick movement of said cross bar toward the other cross bar to effect a group release of the snelled hooks from the frame and stop means adjustably engaged on the side rods to determine the extent of movement of the free sliding cross bar away from the other cross bar. 55
8. Apparatus for use in the manufacture 60 of snelled hooks, comprising a frame composed of side rods, a tie rod connecting said side rods in spaced relation at one end, a cross bar connecting opposite end portions of the side rods in spaced relation, a cross bar freely slidable on the side rods between the tie rod and the first mentioned cross bar, snell tensioning means carried by one of the cross bars and the other cross bar having means for engagement by opposite end portions of snelled hooks and whereby a number of hooks 65 may be engaged and held under tension between said cross bars and means for retaining the freely slidable cross bar in position separated a desired distance from the other cross bar, said retaining means being quickly-releasable to enable quick movement of said cross bar toward the other cross bar to effect a group release of the snelled hooks from the frame. 70
9. Apparatus for use in the manufacture 75 of snelled hooks, comprising a frame composed of side rods, a tie rod connecting said side rods in spaced relation at one end, a cross bar connecting opposite end portions of the side rods in spaced relation, a cross bar freely slidable on the side rods between the tie rod and the first mentioned cross bar, snell tensioning means carried by one of the cross bars and the other cross bar having means for engagement by opposite end portions of snelled hooks and whereby a number of hooks 80 may be engaged and held under tension between said cross bars and means for retaining the freely slidable cross bar in position separated a desired distance from the other cross bar, said retaining means being quickly-releasable to enable quick movement of said cross bar toward the other cross bar to effect a group release of the snelled hooks from the frame and said quick-release retaining means including latches on the sliding cross bar engageable with the side rods and provided with projecting finger pieces by which they may be readily released. 85
10. Apparatus for use in the manufacture 90 of snelled hooks, comprising a frame composed of side rods, a tie rod connecting said side rods in spaced relation at one end, a cross bar connecting opposite end portions of the side rods in spaced relation, a cross bar freely slidable on the side rods between the tie rod and the first mentioned cross bar, snell tensioning means carried by one of the cross bars and the other cross bar having means for engagement by opposite end portions of snelled hooks, whereby a number of hooks 95 may be engaged and held under tension between said cross bars and means for retaining the freely slidable cross bar in position separated a desired distance from the other cross bar, said retaining means being quickly-releasable to enable quick movement of said cross bar toward the other cross bar to effect a group release of the snelled hooks from the frame and stop means adjustably engaged on the side rods to determine the extent of movement of the free sliding cross bar away from the other cross bar. 100
11. Apparatus for use in the manufacture 105 of snelled hooks, comprising a frame composed of side rods, a tie rod connecting said side rods in spaced relation at one end, a cross bar connecting opposite end portions of the side rods in spaced relation, a cross bar freely slidable on the side rods between the tie rod and the first mentioned cross bar, snell tensioning means carried by one of the cross bars and the other cross bar having means for engagement by opposite end portions of snelled hooks and whereby a number of hooks 110 may be engaged and held under tension between said cross bars and means for retaining the freely slidable cross bar in position separated a desired distance from the other cross bar, said retaining means being quickly-releasable to enable quick movement of said cross bar toward the other cross bar to effect a group release of the snelled hooks from the frame and stop means adjustably engaged on the side rods to determine the extent of movement of the free sliding cross bar away from the other cross bar. 115
12. Apparatus for use in the manufacture 120 of snelled hooks, comprising a frame composed of side rods, a tie rod connecting said side rods in spaced relation at one end, a cross bar connecting opposite end portions of the side rods in spaced relation, a cross bar freely slidable on the side rods between the tie rod and the first mentioned cross bar, snell tensioning means carried by one of the cross bars and the other cross bar having means for engagement by opposite end portions of snelled hooks and whereby a number of hooks 125 may be engaged and held under tension between said cross bars and means for retaining the freely slidable cross bar in position separated a desired distance from the other cross bar, said retaining means being quickly-releasable to enable quick movement of said cross bar toward the other cross bar to effect a group release of the snelled hooks from the frame. 130

ment of said cross bar toward the other cross bar to effect a group release of the snelled hooks from the frame, the means aforesaid by which the snelled hooks are held at their 5 opposite ends including spaced seats for the hook portions, on one of the cross bars, and correspondingly spaced spring tensioned holding hooks for the loops of the snells on the other of the cross bars.

10 11. Apparatus for use in the manufacture of snelled hooks, comprising a frame composed of side rods, a tie rod connecting said side rods in spaced relation at one end, a cross bar connecting opposite end portions of 15 the side rods in spaced relation, a cross bar freely slideable on the side rods between the tie rod and the first mentioned cross bar, snell tensioning means carried by one of the cross bars and the other cross bar having 20 means for engagement by opposite end portions of snelled hooks and whereby a number of hooks may be engaged and held under tension between said cross bars and means for retaining the freely slideable cross bar 25 in position separated a desired distance from the other cross bar, said retaining means being quickly releasable to enable quick movement of said cross bar toward the other cross bar to effect a group release of the 30 snelled hooks from the frame, a second tie rod connecting the side rods and the first mentioned cross bar being engaged with the side rods in between the two tie rods aforesaid and having means by which the same 35 may be secured in differently set positions on the side rods to facilitate the handling 40 of hooks of different snell lengths.

12. A frame for use in the manufacture of snelled hooks and comprising substantially 45 parallel relatively separable cross bars, hair pin shaped wires slidably engaged in spaced relation in one of said cross bars and having oppositely turned hooks at the free ends of the same, springs engaged between the 50 cross bar and the loops of said hair pin wires, the other cross bar having means for spacedly supporting the hook portions of the hooks whose snells are engaged with the hair pin hooks and readily releasable means for retaining the cross bars in the separated relation.

55 13. Racking means for snell hook manufacture, comprising a frame composed of side rods, tie rods securing opposite end portions of the side rods in spaced parallel relation, a cross bar and means for adjustably securing the same in desired position on the side rods in between the tie rods aforesaid, a second cross bar slidably sleeved 60 on the side rods, latch means for releasably retaining said cross bar in definitely separated relation from the first cross bar, stop means adjustably secured on the side rods for determining the separating movement of 65 the sleeved cross bar from the first cross

bar, spaced snell engaging means on one of the cross bars, correspondingly spaced hook engaging means on the other cross bar and said means on one of the cross bars being yieldable to individually tension the snelled 70 hooks held between the cross bars.

In testimony whereof I affix my signature.
HAROLD W. MEYER.
